CLAIM

The ornamental design for a utility rack, as shown and described.

DESCRIPTION

FIG. 1 is a perspective view of a first embodiment of a utility rack;

FIG. 2 is a front plan view thereof;

FIG. 3 is a right plan view thereof;

FIG. 4 is a left plan view thereof;

FIG. 5 is a top plan view thereof;

FIG. 6 is a bottom plan view thereof; and,

FIG. 7 is a rear plan view thereof.

The broken lines in the drawings indicate unclaimed portions and form no part of the claimed design.

1 Claim, 7 Drawing Sheets
